UNITED STATES PATENT OFFICE.

JOHN G. KLETT, OF BROOKLYN, NEW YORK.

CLASP.

SPECIFICATION forming part of Letters Patent No. 233,774, dated October 26, 1880.

Application filed August 14, 1880. (No model.)

To all whom it may concern:

Be it known that I, JOHN G. KLETT, of Brooklyn, Kings county, New York, have invented a new and Improved Clasp, of which 5 the following is a specification.

The object of my invention is to provide a new and improved clasp for pocket-books, satchels, &c., which is simple in construction, efficient, and convenient in use.

10 The invention consists in a spring-plate provided with a knob or button, and with flanges on the opposite ends, one of which flanges is securely attached to one part of the frame of a pocket-book, satchel, &c., whereas the other 15 flange catches on a stud on the other part of the frame, or catches on the edge of the frame itself, thereby holding the two parts of the frame together and locking the pocket-book.

In the accompanying drawings, Figure 1 is 20 a cross-sectional elevation of the frame of a pocket-book provided with my improved clasp, the pocket-book being closed. Fig. 2 is a cross-sectional elevation of the frame of a satchel provided with my improved clasp, showing the 25 satchel opened; and Fig. 3 is a plan view of a part of the frame of a pocket-book or satchel provided with my improved clasp.

Similar letters of reference indicate corresponding parts.

30 A plate, A, of some suitable spring metal, is provided with a narrow flange, B, and a broad flange, C, at two opposite ends, and the broad flange C is riveted, soldered, or otherwise suitably attached to the part D of the frame of a pocket-book, satchel, &c., or made integral therewith in such a manner that the plate A 35 projects over the said part D of the frame, as shown.

The part E of the pocket-book frame is provided with a stud, F, beveled toward the inner edge, on which stud the narrow flange B of the plate A catches on the outer edge of the part E of the frame. 40

The part D of the frame passes below the part E, and the plate A passes over the part 45 E, as shown.

By pressing the two parts together the flange B catches on the stud F, or on the outer edge of the part E, and thus holds the two parts of the frame together, thereby locking the book. 50

By holding the part E of the frame and pressing the knob or button G, attached to the top of the plate A, in the direction of the arrow a', the flange B is released from the stud F, and the frames can be separated. 55

As the plate A is made of spring metal, no springs are required, and the clasp virtually consists only of a single part, which cannot get out of order, locks the book in a reliable manner, and is easily operated. 60

This clasp may be used for pocket-books, satchels, cigar-cases, portfolios, albums, &c.

Having thus described my invention, I claim as new and desire to secure by Letters Patent— 65

The combination, with a pocket-book frame having parts D E, of the spring-plate A, having flanges B C, the flange B arranged to catch on a beveled stud, F, of part E when both of the parts D E are held in place under the plate 70 A, as and for the purpose specified.

JOHN G. KLETT.
